UNITED STATES PATENT OFFICE.

WILLIAM C. COMMONS, OF WOONSOCKET, RHODE ISLAND, ASSIGNOR TO THE TAFT-PEIRCE MANUFACTURING COMPANY, OF WOONSOCKET, RHODE ISLAND, A CORPORATION OF RHODE ISLAND.

DESIGN FOR A SURFACE PLATE.

47,686.

Specification for Design.

Patented Aug. 10, 1915.

Application filed February 17, 1915. Serial No. 8,925. Term of patent 14 years.

To all whom it may concern:

Be it known that I, WILLIAM C. COMMONS, a citizen of the United States, and a resident of the city of Woonsocket, in the county of Providence, State of Rhode Island, have invented a new, original, and ornamental Design for a Surface Plate, of which the following is a specification, reference being had to the accompanying drawings, forming a part thereof.

Figure 1 is a plan view looking directly at the top of the plate. Fig. 2 is a side view. Fig. 3 is a bottom view looking directly at the underneath portion of the plate.

The upper portion of the plate in the design comprises a series of small squares, as

is clearly shown by Fig. 1. The lower or under part of the plate includes a design formed by nests of webs arranged to form triangles symmetrically arranged with reference to the middle transverse line of the plate. The over-hang of the plate is supported by brackets arranged adjacent the outer edges of the outer triangles substantially as shown.

I claim:—

The ornamental design for a surface plate as shown and described.

WILLIAM C. COMMONS.
